SANITARY DOG TOILET

Frances Bloom, Los Angeles, Calif.

Application March 9, 1953, Serial No. 23,961

Term of patent 14 years

(Cl. D12—2)

To all whom it may concern:

Be it known that I, Frances Bloom, a citizen of the United States of America, and a resident of Los Angeles, county of Los Angeles, State of California, have invented a new, original, and ornamental Design for a Sanitary Dog Toilet, of which the following is a specification, references being had to the accompanying drawing forming a part thereof.

In the drawing:

I claim:

The ornamental design for a sanitary dog toilet, substantially as shown.

FRANCES BLOOM.
